UNITED STATES PATENT OFFICE.

JOHN C. CROMWELL AND CARL W. A. KOELKEBECK, OF CLEVELAND, OHIO.

BLAST-FURNACE TOP.

SPECIFICATION forming part of Letters Patent No. 724,670, dated April 7, 1903.

Application filed September 24, 1902. Serial No. 124,603. (No model.)

To all whom it may concern:

Be it known that we, JOHN C. CROMWELL and CARL W. A. KOELKEBECK, of Cleveland, Cuyahoga county, Ohio, have invented a new and useful Blast-Furnace Top, of which the following is a full, clear, and exact description, reference being had to the accompanying drawings, forming part of this specification, in which—

10 Figure 1 is a top plan view, partly broken away, of our improved top; and Fig. 2 is a vertical central section of the same, the bell and hopper being indicated in dotted lines.

Our invention relates to the construction 15 of the tops of blast-furnaces, and is designed to do away with the radial brackets in the masonry shaft and afford a simple and strong construction.

In the drawings, 2 represents the outer metal 20 shell of the shaft, 3 the inner masonry shaft, and 4 the space between them, which may be provided with a suitable filling of broken slag or other material. The masonry shaft is stepped inwardly at the top to give the usual 25 inwardly-converging shape, while the metal shell 2 extends vertically upward and is connected at its top by a horizontal plate or plates 5, forming the top working platform of the furnace, to the flanged ring 6, supporting the 30 hopper 7. To support the inner periphery of the top plate or plates 5, supporting the ring 6, from which the hopper is hung, we provide radial braces 8 in the form of segmental plates having vertical longitudinal 35 ribs, these plates extending at an angle from the shell 2 and upwardly to the position of the ring 6, where they are connected to said top plate or plates 5. These braces do not form a closed top, there being spaces between their 40 edges, and merely act as bracing-supports.

The advantages of our invention result 45 from the supporting of the top plate or plates of the furnace by the inclined braces or supports springing from the outer metallic shell of the stack, a simple and strong construction being afforded thereby. We have shown the down-comer 9 as extending through the top plate 5 and into one of the brace-plates 8, a hole 10 being formed through the inwardly-50 converging masonry stack to lead the gases to the down-comer.

Many variations may be made in the form

and arrangement of the parts without departing from our invention.

We claim—

1. A blast-furnace having an outer vertically-extending metal shell, an inner masonry stack, a horizontally-extending metal top plate surrounding the opening in the top of the furnace and connected to the outer shell, and 50 radial upwardly-inclined braces entirely outside the masonry stack and connected to the metal shell and to the top plate at or near the inner edge of the latter, said top plate being entirely outside the masonry stack and forming 55 the working platform at the top of the furnace, substantially as described.

2. A blast-furnace having an outer vertically-extending metal shell, an inner masonry stack, a horizontal metal top plate connected 7c to the outer metal shell and extending inwardly to the opening in the top of the furnace, and radial brace-plates connected to the outer shell and extending entirely outside the masonry and inwardly and upwardly and connected to the metal top plate at or near its 75 inner edge, said top plate being entirely outside the masonry stack and forming the working platform at the top of the furnace, substantially as described. 80

3. A blast-furnace having an outer vertically-extending metal shell, a horizontally-extending metal top plate surrounding the opening in the top of the furnace and connected to said shell, inclined brace-plates outside the masonry and connected to the outer metal shell and extending upwardly and inwardly and connected to the top plate at or near its inner edge, and a down-comer extending through the top plate and connected to 85 the brace-plates, substantially as described. 90

4. A blast-furnace having an outer vertically-extending metal shell, an inner masonry stack, a horizontally-extending metal top plate surrounding the opening in the top of the 95 furnace and connected to the outer shell, and radial upwardly-inclined brace-plates having their greatest area disposed in the plane of their inclination and connected to the shell and to the top plate; said top plate being entirely outside the masonry stack and forming the working platform at the top of the furnace, substantially as described. 100

5. A blast-furnace having an outer verti-

cally-extending metal shell, an inner masonry stack, a horizontally-extending metal top plate surrounding the opening in the top of the furnace and connected to the outer shell, and
5 radial upwardly-inclined brace-plates disposed closely together forming a substantially continuous brace around the furnace and connected to the shell and to the top plate; said top plate being entirely outside the masonry stack and forming the working plat-

form at the top of the furnace, substantially as described.

In testimony whereof we have hereunto set our hands.

JOHN C. CROMWELL.
CARL W. A. KOELKEBECK.
